(57) **CLAIM**

The ornamental design for a product merchandising rack, as shown and described.

DESCRIPTION

FIG. 1 is a perspective view of a product merchandising rack showing our new design.

FIG. 2 is a front elevational view thereof.

FIG. 3 is a rear elevational view of thereof.

FIG. 4 is a left side elevational view thereof.

FIG. 5 is a right side elevational view thereof.

FIG. 6 is a top plan view thereof.

FIG. 7 is bottom plan view thereof.

FIG. 8 is a perspective view of another embodiment of the product merchandising rack of FIGS. 1-7 showing our design.

FIG. 9 is a front elevational view of the embodiment shown in FIG. 8.

FIG. 10 is a rear elevational view of the embodiment shown in FIG. 8.

FIG. 11 is a left side elevational view of the embodiment shown in FIG. 8.

FIG. 12 is a right side elevational view of the embodiment shown in FIG. 8.

FIG. 13 is a top plan view of the embodiment shown in FIG. 8; and,

FIG. 14 is a bottom plan view of the embodiment shown in FIG. 8.
